(57) **CLAIM**

The ornamental design of a bottle body, as shown and described.

DESCRIPTION

FIG. 1 is a front view of the bottle body showing our new design.

FIG. 2 is a top view of the bottle body shown in FIG. 1.

FIG. 3 is a side view of the bottle body shown in FIG. 1.

FIG. 4 is a bottom view of the bottle body shown in FIG. 1, the bottom of the bottle body being open; and,

FIG. 5 is similar to FIG. 4 but the view is inclined from the bottom view shown in FIG. 4.

No color is claimed as part of the design.

1 Claim, 5 Drawing Sheets
